(57) **CLAIM**

I claim the ornamental design for a nozzle, as shown and described.

DESCRIPTION

FIG. 1 is a front view of the nozzle of my new design;
FIG. 2 is a bottom view of the nozzle of my design;
FIG. 3 is a view looking along the top outlet of the nozzle
of my design;

FIG. 4 is a side view thereof;

FIG. 5 is a side view as viewed from the opposite side seen
in FIG. 4; and,

FIG. 6 is a perspective of the nozzle of my design.
